UNITED STATES PATENT OFFICE.

ALBERT H. DE VOE, OF ELIZABETH, NEW JERSEY, ASSIGNOR TO THE SINGER MANUFACTURING COMPANY, A CORPORATION OF NEW JERSEY.

RUFFLING AND STITCHING MACHINE.

1,094,707.

Specification of Letters Patent. Patented Apr. 28, 1914.

Application filed April 2, 1910. Serial No. 552,948.

To all whom it may concern:

Be it known that I, ALBERT H. DE VOE, a citizen of the United States, residing at Elizabeth, in the county of Union and State 5 of New Jersey, have invented certain new and useful Improvements in Ruffling and Stitching Machines, of which the following is a specification, reference being had therein to the accompanying drawings.

10 This invention relates to an improvement in that class of machines which are designed to effect the folding of the edges and the ruffling and stitching of continuous bands upon the bottoms of skirts, and for performing 15 this class of work upon other circular articles, and it has for its object to provide convenient and effective means for adjusting the several coacting parts for efficient cooperation in the handling of the work and 20 to facilitate the disengagement of certain of the work-engaging parts near the completion of a seam to enable the latter to be finished at the starting point.

The invention consists in the several constructive features herein shown and 25 described and set forth in the appended claims.

In the drawings, Figure 1 is a rear side elevation of a sewing machine embodying 30 the present improvements, and Fig. 2 a front end elevation of the same with the face-plate removed and the work-plate in section. Fig. 3 is a perspective view, upon a larger scale, showing the ruffling and folding 35 devices detached from other parts of the machine, with the presser-foot raised and the coöperating parts separated for introduction of the work; and Fig. 4 is a similar view of certain of the same parts, taken 40 from a different view point. Fig. 5 is a sectional plan view representing the adjustable connection between the swinging ruffling lever and its vibratory actuating arm, and Fig. 6 a perspective view of the pointer- 45 carrying washer applied to such connection. Fig. 7 is a detail perspective view of the clamping washer for one of the adjustable stop-members of the device. Fig. 8 is a perspective view of the tape-guiding presser- 50 foot, and Fig. 9 a similar view of the ruffling blade and its carrying arm. Fig. 10 is a perspective view representing the product of the machine with a portion thereof uncompleted.

55 The present improvement is shown em-

bodied in the well-known Singer double-chain-stitch machine disclosed more fully in my application Serial No. 501,460, filed June 11, 1909, and comprising a frame having the base 1 and bracket-arm formed with hollow 60 standard 2 and overhanging portion 3 in the head 4 of which is journaled a vertically reciprocating needle-bar 5 carrying the needles 6 arranged in a plane at an angle with the line of feed and coöperating with the 65 thread-carrying loopers 7 in the production of parallel double-chain-stitch seams, the under ply of the work being advanced by the action of the feed-dog 8 carried by the feed-bar 9 in a manner well known. The pressure 70 member 10 of the presser-foot, opposed to the feed-dog 8, is pivotally attached, by means of the pin 11, to the shank 12 which is secured by means of the fastening screw 13 to the reduced lower end of the presser- 75 bar 14 mounted in the head 4 of the bracket-arm and having its upper end engaged by the free end of the pressure spring 15 whose opposite end rests upon the top of the bracket-arm member 3 and is held in position by the steady-pin 16 thereon, pressure 80 being maintained upon the top of the presser-bar by means of the adjusting screw 17 tapped into a lug 18 upon the arm 3 overhanging the spring 15 which is engaged by 85 the point of said screw. The upturned forward portion 19 of the presser-foot is formed with a tape-guiding channel 20.

The main-shaft 21, journaled in the base 1 beneath the work-plate 22, carries at its 90 rearward end an actuating eccentric 23 embraced by a strap 24 at the lower end of an eccentric-rod 25 connected at its upper end by means of the stud 26 with a forwardly projecting arm 27 having a hub 28 secured 95 by means of set-screws 29 upon the rearward end of the ruffler rock-shaft 30 journaled in suitable bearings 31 and 32 upon the back of the bracket-arm member 3. The rock-shaft 30 carries near its forward end 100 the hub 33 of a lateral arm 34 connected by means of the stud 35 with the upper end of a link 36 whose lower end embraces a stud 37 carried by a lateral arm 38 extending from a hub 39 which is fixed upon the 105 rock-shaft 40 journaled in the lower portion of the head 4 of the bracket-arm beneath the rock-shaft 30. The rock-shaft 40 has fixed upon its forward end a depending arm 41 formed with a longitudinal undercut guide- 110

way or channel 42 which is entered by the rectangular head 43 of a coupling pin 44 having fitted upon its shank the loose bushing 45 with flange 46 resting upon the outer face of the arm 41. The bushing 45 enters a central aperture in a slide-block 47 fitted within a longitudinal slideway 48 in the ruffling lever 49 which is pivotally supported by means of the stud-screw 50 tapped into a lateral arm 51 having its hub 52 fixed upon the fulcrum-pin 53 journaled upon the head 4 of the bracket-arm and connected at its opposite end by means of the stud-screw 54 with a split collar 55 adjustably secured by means of clamp-screws 56 upon the presser-bar 14.

As will be observed by reference to Fig. 2, in which the ruffling blade is shown in its advance position, the guideways 42 and 48 of the crank-arm 41 and ruffling lever 49, respectively, are disposed in parallel relation and in a diametrical plane of the actuating rock-shaft 40. By this means, no matter what is the position of adjustment of the slide-blocks 43 and 47 in such guideways, the ruffling lever 49 will invariably assume an extreme advance position at the same point, and the operative edge of the ruffling blade will accordingly assume its advance position at a fixed point relatively to the needles regardless of the amplitude of its operative or ruffling movements. By mounting the crank-arm 41 upon the actuating rock-shaft at the outer extremity of the bracket-arm and the ruffling lever beyond the same, these parts are adapted to be arranged not only backward of the stitching mechanism to facilitate the handling and inspection of the work by the operator, but ample provision is made for properly positioning the fulcrum-stud of the ruffling lever to provide the necessary separation of the axes of movement of such lever and its actuating crank-arm to provide for the desired adjustment of throw of the former by its connection with the latter. As an additional advantage of this arrangement the adjusting means for varying the position of the slide-blocks 43 and 47 is exposed in the most accessible position for manipulation by the operator.

The vibrating ruffling lever 49 has at its lower end the rearwardly and downwardly projecting lug 57 entering the fork 58 at the rearward end of the ruffling blade carrying arm 59 to which it is pivotally attached by means of the screw-stud 60. The arm 59 has at its forward or free end the lateral ear 61 formed in its under side with a longitudinal seat 62 to receive the shank 63 of the ruffling blade 64 serrated and sharpened at its forward end and having tapped in the upper side of its shank the fastening screw 65 passing through a longitudinal slot 66 in the ear 61 by means of which it is

adjustably secured to its carrying arm 59. The coupling pin 44 has applied to its threaded outer end the internally threaded bushing 67 provided with the flange 68 adapted to rest in contact with the outer end 70 of the bushing 45 and to overlap the slide-block 47, this bushing having its cylindrical body fitted within the split socket 69 of a clamp-lever 70 provided with ears 71 which are normally drawn together to clamp the 75 lever upon the bushing 67 by means of a screw 72. The bushing 67 may be turned by the lever 70 in clamping and unclamping between the coupling pin head 43 and the bushing-flange 46 the slotted outer portion 80 of the rocking arm 41 from which operative movements of the ruffling lever 49 are derived. The hub of the lever 70 may obviously be clamped upon the bushing 67 in such manner that when the bushing is tightened to clamp the coupling pin 44 in position upon the vibratory arm 41 the lever 70 will lie in its rearward position where it is least in the way of the operator, and this adjustment may be changed from time to 90 time to compensate for wear of the clamping parts.

The forked rearward portion of the arm 59 carries a lateral pin 73 formed in its upper side with a suitable cavity or pocket 74 to receive the lower extremity of a threaded thrust-rod 75 loosely journaled near the upper end in a perforated ear 76 upon the forward edge of the lever 49 and passing through an internally threaded slide-block 77 having in its rearward edge a groove adapted to engage a guide-rib 78 formed upon the forward edge of the lever 49, a spring 75* being interposed between the ear 76 and the block 77 whereby an adjustable 105 downward pressure is exerted upon the thrust-rod which is communicated to the pin 73 and thence through the arm 59 to the ruffling blade 64.

Fixed upon the presser-bar 14 below the collar 55 by means of screws 79 and 80 are collars 81 and 82 provided respectively with forwardly extending bearing lugs 83 and 84 having alined bearing apertures in which are journaled the opposite end portions of an oscillatory slide-rod 85 having upon its lower end a radial wing 86 fitted within a lateral channel or recess 87 of the separator-carrying arm 88 adjustably secured to said wing by means of a fastening screw 89 passing through a slot 90 in the latter and tapped into the arm 88. The arm 88 is formed at its free outer end with a lateral flange or supporting plate 91 affording a seat upon which is secured by means of the fastening screws 92 the shank 93 of the separator-plate 94 normally disposed beneath the ruffling blade 64 and having its forward edge notched and serrated as represented in Fig. 3 and formed in its upper face with 130

longitudinal grooves to receive the points or serrations of the ruffling blade. The supporting plate 91 has also in its upper face a transverse groove in which is adjustably secured by means of the screw 95 entering a slot 96 therein the shank 97 of the upper edge-folder 98. The slide-rod 85 has secured thereon near its upper end by means of the screw 99 a split collar 100 having secured thereon by means of the screw 101 the shank of an upwardly extending latch-tooth 102 adapted to engage the rounded cam face extending along the outer side and the bottom of the forwardly projecting lug 103 which is formed in its front side at the end of said cam-face with a slot 104 to be entered by the upper portion of the tooth 102 under the action of a spring 105 interposed between the collar 100 and the lower bearing lug 84. The collar 100 is provided with a forwardly extending finger-piece 106 by means of which the slide-rod 85 may be pressed downwardly in opposition to its spring 105 to disengage the tooth 102 from the slot or aperture 104 so as to enable the rod to be turned for shifting the separator-plate and upper edge folder from the operative position represented in Figs. 1 to 4 inclusive, to inoperative position.

30 The face-plate 4* carries a stud-screw 107 passing through a washer 108 formed in its inner face with a groove 108* between which and the face-plate is interposed an endwise adjustable rod 109 having a lateral stop-finger 110 disposed in advance of the cam-lug 103. When the presser-foot is lowered, the slide-rod 85 assumes a lower position in which the latch-tooth 102, while entering the lower portion of the slot 104, remains out of contact with the stop-finger 110, but when the presser-foot is raised, the slide-rod rises with the same under the action of the spring 105 until the upper edge of the tooth 102 comes into contact with the stop-finger 110, 45 when its upward movement is checked and the continued upward movement of the bearing lugs 83 and 84 thereof serves merely to compress the spring 105.

50 The collar 82 has formed therein adjacent the presser-bar 14 a vertical socket in which is adjustably secured by means of the fastening-screw 111 the shank of a depending lifting rod 112 provided at its lower end with a lateral finger 113 extending beneath the lower edge of the ruffler-blade carrying arm 59 to insure the lifting of the latter with the rise of the presser-foot for the introduction and removal of the work. The guide for the margin of the body fabric is afforded by the edge-folder 114 whose base-plate 115 is adjustably secured upon the work-plate slide 22* by suitable means which form no part of the present improvement.

60 The presser-bar 14 has secured thereto beneath the collar 81 by means of the screw

116 still another collar 117 which is provided with a rearwardly projecting lug 118 extending through a slot 119 in the rear side of the bracket-arm head 4 for engagement with the cammed upper portion 120 of the lifting lever 121 mounted upon the fulcrum-pin 122 in a manner well known.

As represented in the drawings, the slotted portion of the swinging ruffling lever 49 is shown provided along its rearward edge 75 with a series of graduations 123 to form a scale over which lies the pointer 124 formed upon an angular extension 125 of a washer 126 having an aperture 127 embracing the periphery of the bushing flange 46, the angular extension 125 being fitted to the adjacent edge of the lever 49. The position of the fulcrum-pin 44 and the corresponding stroke of the ruffling blade under the uniform vibratory movements of the arm 41 85 are indicated by the pointer 124 in connection with the scale 123 which latter is in practice provided with suitable numbers representing the different ranges of movement of the ruffler blade. 90

In the operation of the machine, the presser-bar is first lifted by means of the finger-lever 121, or by means of the treadle-actuated rock-lever 128 fulcrumed upon the arm 3 at 129 for introduction of the several 95 plies of fabric. The presser-foot being directly attached to the presser-bar follows the full lift of the latter. As the fulcrum-pin 50 of the ruffling lever 49 is mounted upon the arm 51 intermediate its fulcrum 53 100 and the stud 54 by which it is connected with the presser-bar, it will be seen that the lever 49 is positively lifted, but in a lesser degree than the presser-bar, and in its upward movement it lifts the fulcrum-pin 60, while 105 the spring-actuated thrust-rod 75 continues to act upon the lateral stud 73 of the arm 59 to force the ruffling blade downward in opposition to the lifting action of the separator-plate which rises with its supporting 110 slide-bar 85 under the action of the spring 105 until its upward motion is checked by engagement of the tooth 102 with the stop-finger 110 as previously described. The ruffling blade ceases its rising movement 115 with that of the separator-plate until its carrying arm 59 is engaged by the lateral finger 113 of the depending lifting rod 112, when the ruffling blade is lifted to its highest position which is above the extreme elevated 120 position of the separator-plate but slightly below the bottom of the presser-foot at the highest point of the latter. By the means above described, the several parts acting upon the ruffled fabric are differentially 125 lifted by the raising of the presser-foot so as to afford intervening spaces for the convenient insertion of the several plies of fabric, the tape being introduced into the guiding channel-way 20 of the presser-foot and 130

beneath the sole of the latter above the ruffling blade, the marginal portion of the upper ply of fabric being introduced from the right into the upper fold-guide 98 and 5 led forwardly beneath the needles and between the ruffling blade and separator-plate, and the lower or body fabric being introduced from the left into the lower fold-guide 114 beneath the separator-plate. The 10 several plies of fabric having been introduced as above described, the presser-bar is lowered, when the several parts assume their operative positions in yielding engagement with the work.

15 In the folding, ruffling and stitching of circular articles, such as skirts, the operation proceeds from the initial point up to within a short distance of return to the same point, when it is necessary to withdraw the 20 folders from the folded edges of the two lower plies of fabric. To this end the presser-foot is raised as before, and the finger-piece 106 is pressed downwardly to force the slide-rod 85 downwardly for dis- 25 engagement of the latch-tooth 102 from the cam-lug 103, which enables the operator to turn the slide-rod 85 so as to shift the carrier 88 with its separator-plate 94 and upper edge-folder 98 into inoperative position 30 at the side of the stitch-forming mechanism, thus disengaging such members from the ruffled fabric. The folded edge of the lower 35 ply of fabric is readily disengaged from the lower edge-folder 114, after which the 40 presser-bar is again lowered and the remainder of the seam is guided by hand to the stitch-forming mechanism for completion of the operation. The lifting of the presser-bar permits the removal of the work, as in ordinary sewing machines.

In returning the separator-plate and upper edge-folder to initial position, it is merely necessary to throw the finger-piece 106 toward the front of the machine, when 45 the latch-tooth 102 rides down the inclined cam edge of the lug 103 until it strikes the depending farther side wall of the slot 104, when the spring 105 causes it to snap into the latter to lock the parts mounted upon 50 the carrier 88 in operative relation with the co-operating parts.

55 Referring to Fig. 10, it will be observed that the lower ply or body-fabric *a* has its marginal portion *a'* turned over upon itself to receive the partially overlapping under-turned margin *b'* of the ruffle-fabric *b*, these overlapped folds of the two fabrics being covered by the folded tape *c* and all stitched together by the parallel seams *d* and *e*, the 60 former of which passes through the tape and the folded margin of the body fabric, while the latter passes through all three fabrics.

Having thus set forth the nature of the invention, what I claim herein is:—

65 1. In a sewing machine, the combination

with stitch-forming mechanism including a reciprocating needle, feeding mechanism, a presser-bar, and a presser-foot carried thereby, of a swinging ruffling lever, a ruffling blade, a carrier therefor fulcrumed upon 70 said ruffling lever, a spring acting upon said carrier to press the ruffling blade downwardly in operative relation with the work, a separator-plate, a carrier therefor, a spring 75 connected with the separator-plate carrier for pressing the same upwardly, a lifting member carried by the presser-bar and normally out of operative engagement with the ruffling blade carrier but adapted to engage the same to lift said carrier, a fixed stop 80 for arresting the lifting movement of the separator-plate carrier, and a lifting device for the presser-bar whereby the presser-foot, ruffling blade and separator-plate are differentially lifted to admit the work. 85

2. In a sewing machine, the combination with stitch-forming mechanism including a reciprocating needle, feeding mechanism, a presser-bar, and a presser-foot carried thereby, of a swinging ruffling lever, a ruffling 90 blade, a carrier therefor fulcrumed upon said ruffling lever, a spring acting upon said carrier to press the ruffling blade downwardly in operative relation with the work, a separator-plate, a carrier therefor, a spring 95 connected with the separator-plate carrier for pressing the same upwardly, a lifting member adjustably secured to the presser-bar and normally out of operative engagement with the ruffling blade carrier but adapted to engage the same to lift said carrier, a stop adjustably secured upon a fixed support and adapted for arresting the lifting movement of the separator-plate carrier, and a lifting device for the presser-bar whereby the presser-foot, ruffling blade and separator-plate are differentially lifted to admit the work. 100

3. In a sewing machine, the combination with stitch-forming mechanism including a reciprocating needle, and feeding mechanism, of a swinging ruffling lever having a longitudinal slideway and an adjacent graduated scale and adapted to move in a plane parallel with that of the needle path, a ruffling blade, a carrier therefor pivotally mounted upon said ruffling lever, an actuating rock-shaft mounted in fixed bearings and provided with a crank-arm adjacent said ruffling lever, means for imparting uniform operative movements to said rock-shaft, a pivotal stud carried by said crank-arm and provided with means whereby it is adjustable longitudinally of the latter, a slide-block mounted upon said stud and entering said slideway in the ruffling lever, and a pointer overlying said scale of the ruffling lever and movable with said pivotal stud to indicate the range of throw of the ruffling lever and ruffling blade under the 110 115 120 125 130

uniform operative movements of said crank-arm.

4. In a sewing machine, the combination with stitch-forming mechanism including a reciprocating needle, and feeding mechanism, of a swinging ruffling lever adapted to move in a plane parallel with that of the needle-path and provided at one edge with a bearing lug and an adjacent longitudinal guide-rib, a ruffling blade, a carrying arm therefor pivotally mounted upon said ruffling lever, an actuating rock-shaft mounted in fixed bearings and provided with a crank-arm adjacent said ruffling lever, operating means for said rock-shaft, a pivotal stud carried by said crank-arm and affording a coupling between the latter and said ruffling lever, a thrust-rod having one end portion journaled in the bearing lug of the ruffling lever and the opposite end connected with the ruffling blade carrier, a slide-block adjustably mounted upon and intermediate the ends of said thrust-rod and grooved to embrace said guide-rib, and a spring interposed between said bearing lug and slide-block and acting through said thrust-rod and carrier to press the ruffling blade upon the work.

5. In a sewing machine, the combination with stitch-forming mechanism and feeding mechanism, of ruffling mechanism including a swinging ruffling lever, a ruffling blade, a carrying arm therefor pivotally connected at one end with said ruffling lever and having at its opposite end a lateral ear formed with a longitudinally extending slot and having in its under side a seat having lateral shoulders fitted to the edges of the ruffling blade, and a fastening screw with its shank entering the slot in said lateral ear and tapped into the ruffling blade and having its head seated upon the top of said ear, whereby the longitudinal adjustment of the ruffling blade upon said arm may be effected from the upper side of the same while the ruffling blade is held against lateral displacement.

6. In a sewing machine, the combination with stitch-forming mechanism including a reciprocating needle, feeding mechanism, a presser-bar, and a presser-foot carried thereby, of a swinging ruffling lever, a ruffling blade, a carrier therefor fulcrumed upon said ruffling lever, a spring acting upon said carrier to press the ruffling blade downwardly in operative relation with the work, a separator-plate, a carrier therefor, an oscillatory slide-rod movable relatively to and parallel with the presser-bar, spaced bearing bosses in which said slide-rod is journaled, a lug projecting from the upper bearing boss and provided upon its lower side with a cam surface terminating in a slot parallel with the slide-rod, a collar fixed upon the slide-rod and carrying an upwardly extend-

ing latch-tooth adapted to engage said cam surface and enter the adjacent slot, and a spring for normally pressing said slide-rod upwardly.

7. In a sewing machine, the combination with stitch-forming and feeding mechanisms, of a swinging ruffling lever, a ruffling blade, a carrier therefor pivotally connected with the ruffling lever, means for lifting the ruffling blade out of operative relation with the work, a separator-plate, a carrier therefor, an oscillatory slide-rod, spaced bearing bosses in which said slide-rod is journaled, a lug projecting from the upper bearing boss and provided upon its lower side with a cam surface terminating in a slot parallel with the slide-rod, a collar fixed upon the slide-rod and carrying an upwardly extending latch-tooth and adapted to engage said cam surface and enter the adjacent slot, a spring for normally pressing said slide-rod upwardly to maintain the separator-plate normally in operative relation with the ruffling blade, and an adjustable stop mounted upon a fixed support and disposed within the path of movement of said tooth.

8. In a sewing machine, the combination with the work-plate and stitch-forming and feeding mechanisms, of a presser-bar, a presser-foot carried thereby, a reciprocating ruffling blade, a separator-plate, a presser-bar lifter, and connections disposed rearwardly of the forward end of the presser-foot whereby the raising of the presser-bar causes the lifting of the presser-foot, the ruffling blade and the separator-plate and separation of each of said parts from the others.

9. In a sewing machine, the combination with the work-plate and stitch-forming and feeding mechanisms, of a presser-bar, a presser-foot carried thereby, a presser-bar lifter, a reciprocating ruffling blade, a separator-plate, a carrier therefor movable toward and from the work-plate, an adjustable stop sustained independently of the presser-foot for limiting the range of movement of said carrier away from the work-plate, and lifting means for said carrier.

10. In a sewing machine, the combination with the work-plate and stitch-forming and feeding mechanisms, of a presser-bar, a presser-foot carried thereby, a presser-bar lifter, a reciprocating ruffling blade, a separator-plate, means actuated by the presser-bar lifter whereby the presser-foot, the ruffling blade and the separator-plate are lifted, and means for adjusting the range of lifting movement of the ruffling blade and separator-plate relatively to the presser-foot.

11. In a sewing machine, the combination with the frame including a bed-plate and an overhanging bracket-arm, and stitch-forming and feeding mechanisms, of an actuating rock-shaft journaled in the bracket-arm, a

6
 crank-arm fixed thereon beyond the extremity of the bracket-arm and provided with a radial guideway, a swinging ruffling lever disposed adjacent said crank-arm and
 5 formed with a guideway disposed lengthwise thereof, slide-blocks fitted respectively to the guideways of said ruffling lever and crank-arm, a pivotal stud connecting said slide-blocks, and means including a clamp-lever
 10 applied to said pivotal stud and disposed beyond the outer face of the ruffling lever whereby said slide-blocks are adjustably sustained in position in their respective guideways.
 15 12. In a sewing machine, the combination with the frame including a bed-plate and an overhanging bracket-arm, and stitch-forming and feeding mechanisms, of an actuating rock-shaft journaled in the bracket-arm,
 20 a crank-arm fixed thereon beyond the extremity of the bracket-arm and provided with a radial guideway, a swinging ruffling lever disposed adjacent said crank-arm and formed with a guideway parallel with that
 25 of the crank-arm in one extreme position of the same, slide-blocks fitted respectively to the guideways of said ruffling lever and crank-arm, a pivotal stud connecting said slide-blocks, and means including a clamp-
 30 lever applied to said pivotal stud and disposed beyond the outer face of the ruffling

lever whereby said slide-blocks are adjustably sustained in position in their respective guideways.

13. In a sewing machine, the combination 35 with stitch-forming and feeding mechanisms, a presser-bar carrying a presser-foot, and a presser-bar lifter, of a swinging ruffling lever, actuating means therefor, a ruffling blade connected with and actuated by 40 said lever, and a movable support for said ruffling lever connected with and movable differentially with respect to the presser-bar under the action of said lifter.

14. In a sewing machine, the combination 45 with stitch-forming and feeding mechanisms, a presser-bar carrying a presser-foot, and a presser-bar lifter, of a swinging ruffling lever, a ruffling blade connected with and actuated by said lever, an arm having a fixed fulcrum and a connection with said presser-bar in relation to which it is disposed transversely, a stud carried by said arm upon which the ruffling lever is hung, and actuating means for the ruffling lever. 50 55

In testimony whereof, I have signed my name to this specification, in the presence of two subscribing witnesses.
